Patented Feb. 20, 1962

192,256

PICKLE TONGS OR THE LIKE

Alfred Ackerson, 1-N-629, Glen Ellyn, Ill.

Filed June 21, 1961, Ser. No. 65,673

Term of patent 14 years

(Cl. D44—4)

Fig. 1.

Fig. 2.

Fig. 3.

Fig. 4.

Fig. 5.

FIG. 1 is a perspective view of pickle tongs embodying my new design;

FIG. 2 is an elevational view of one face thereof;

FIG. 3 is an elevational view of one of the two like sides thereof;

FIG. 4 is a fragmentary elevational view of the face thereof opposite that shown in FIG. 2; and

FIG. 5 is a bottom plan view of the tongs.

I claim:

The ornamental design for pickle tongs or the like, substantially as shown.
